UNITED STATES PATENT OFFICE.

ISAAC H. LEVIN, OF NEW YORK, N. Y.

WATER-FEED ATTACHMENT FOR ELECTROLYTIC CELLS.

1,360,543.

Specification of Letters Patent. Patented Nov. 30, 1920.

Application filed April 21, 1919. Serial No. 291,643. Renewed April 23, 1920. Serial No. 376,169.

To all whom it may concern:

Be it known that I, ISAAC H. LEVIN, a citizen of the United States, residing at the borough of Manhattan, in the city, county, 5 and State of New York, have invented certain new and useful Improvements in Water-Feed Attachments for Electrolytic Cells, of which the following is a specification, reference being had therein to the accompanying drawings, which form a part 10 thereof.

My invention relates to water feed attachments for electrolytic cells, and more particularly to a type thereof wherein the fill 15 cup is utilized to permit a blowout in the event of the development of excessive pressures in a cell, or of the level of the electrolyte in the cell becoming too low.

In attachments of the type to which my 20 invention relates, there is a chamber adapted to contain feed water, which chamber communicates, through suitable passages, with the interior of a cell, one end of said passages terminating within said chamber, and 25 the other end thereof being normally below the level of the electrolyte in said cell, so that under normal conditions both ends of the passage are sealed against the escape of gases by the solution in the cell, or the feed 30 water in the chamber. In the event of the electrolyte in the cell getting too low, or the development of excessive pressures in the cell, gases from the cell will escape through the said passages between the cell and the 35 feed water chamber, these gases being imprisoned by the electrolyte in the form of small bubbles, which emerge from the passages with sufficient velocity to spatter electrolyte upon the exterior of the cell.

40 In a device made in accordance with my invention, the gas bubbles, or spray, are permitted to flow freely through the said passages into the said chamber when conditions within a cell are such as to cause a 45 blow-out, means being provided, however, whereby the various small bubbles will be confined within the chamber in a manner to cause them to merge into larger bubbles, said means being so constructed that when 50 said larger bubbles burst, the gas therein will be permitted to escape, but the liquid of the envelop thereof will be returned to the chamber, thus preventing the splashing of this liquid, or the escape of the spray 55 formed by the bubbles, in a manner to foul the cell.

The attachment is so constructed as not to interfere with the free flow of the feed water from the chamber to the cell, or the surging of the electrolyte between the chamber and the cell in the event of varying pressure conditions within the cell. At the same time in the event of a blow-out, a baffle is presented about the mouth of the passage within the chamber, which baffle has gas 65 passages therethrough, a perforated shield inclosing said baffle in a manner to cause the accumulation of gas bubbles upon the under side thereof with the results above referred to.

70 The invention consists primarily in a water-feed attachment for electrolytic cells embodying therein means forming a chamber for feed water, and passages leading from said chamber and discharging within said cell, and a perforated shield within said chamber and above the ends of said 75 passages, whereby gas bubbles emerging from said passages will accumulate upon the under side of said shield, and gas, freed by 80 the bursting of bubbles will pass through said shield and the liquid envelop of said bubbles will be returned to said chamber; and in such other novel features of construction and combination of parts as are herein- 85 after set forth and described and more particularly pointed out in the claims hereto appended.

Referring to the drawings,

Figure 1 is a sectional view of a portion 90 of a cell embodying a feed attachment made in accordance with my invention;

Fig. 2 is a section on the line 2—2 of Fig. 1;

Fig. 3 is a detailed view of the end of the 95 fill pipes within the cup and the baffle and shield upon a larger scale;

Fig. 4 is a plan view of the baffle; and

Fig. 5 is a plan view of the shield.

Like letters refer to like parts throughout 100 the several views.

A water feed attachment made in accordance with my invention may be used with various types of cells, the detailed construction thereof varying to adapt it to the particular construction of each type. In the accompanying drawings, I have illustrated it in connection with a uni-polar generator of the multiple unit type, wherein the cell 105 casing is insulated from the electrodes and is surmounted by a fill cup communicating with the interior of the cell through suitably

arranged fill pipes, and I will particularly describe the invention with relation to this form thereof.

In the embodiment of my invention shown in the drawings, the attachment is shown as being applied to a cell composed of casing members *a* and *b*, having mounted therein an electrode *c* of one polarity, and electrodes *d* and *e* of the opposite polarity, porous, gas-impervious diaphragms *f* and *g*, being disposed between the electrode *c* and the electrodes *d* and *e*, respectively. The casing *a*—*b* is surmounted by a fill cup *h* open at the top and constituting a chamber for the feed water, fill pipes *h'*, *h²* and *h³* forming passages between said cup and the interior of the cell, through which feed water may flow from said cup into said cell to replace that water decomposed while the cell is in operation; through which gases may flow in the event of the level of the electrolyte in the cell becoming too low, and through which electrolyte may surge between the cell and the cup to compensate for varying pressure conditions within the cell. The head of water in the chamber and the passages therefrom communicating with the cell, is sufficient to prevent the escape of gases from the cell under normal working conditions.

To equalize the supply of water delivered upon opposite sides of the diaphragms *f* and *g*, the fill pipes *h'*, *h²* and *h³* project within the cup *h*, the pipe *h'* terminating at a point below that at which the pipes *h²* and *h³* terminate, so as to increase the volume of water delivered between the diaphragms *f* and *g*. The ends of the said fill pipes within the cup are alined as shown, which may be as a matter of convenience and as simplifying the device of the attachment.

The ends of the pipes *h'*, *h²* and *h³* within the cell are equipped with separating devices, which form no part of the present invention, and the ends of said pipes *h²* and *h³*, within the fill cup, are on the same level.

Inclosing this protruding end of each of the pipes *h'*, *h²* and *h³* within the cup *h*, are cup-shaped baffles *i'*, *i²* and *i³*, said baffles being spaced away from the ends of said pipes to an extent to permit the free flow of electrolyte or gas into and from said pipes. Preferably said baffles are made of one single casting, being connected by bridges *j* having thereon upwardly extending studs *i'* and *i²*. The lower edges of the baffles project below the tops of the pipes *h'*, *h²* and *h³*, in fairly close proximity to the bottom of the cup *h* to prevent the escape of bubbles of gas about same, openings *j* being provided in the top of each baffle to permit the escape of such bubbles or any free gas.

Supported by the studs *i'* and *i²* is a perforated shield *k* having a down-turned edge extending about said baffles, the perfora-

tions of said shield being sufficiently small to prevent the escape of gas bubbles therethrough, thus causing such bubbles to accumulate on the under side of the shield, where, as a result of contact with each other, they will merge into larger bubbles which in turn will burst, the gas flowing freely through the openings in said shield and the liquid of the envelop of such bubbles falling within the cup, or upon the baffles, or following the edges of the shield until such liquid is ultimately returned to the cup *h*.

The operation of the herein described attachment is substantially as follows:

When a cell has been charged with the electrolyte, distilled water is delivered to the fill cup *h* until the various baffles and the shield *k* are completely submerged therein. Under normal working conditions, as the electrolyte is decomposed and the gases are withdrawn from the cell, this water will flow through the fill pipes *h'*, *h²* and *h³* into the cell, as required to replace the decomposed water.

Ordinarily cells of the character to which my invention relates, are used in large batteries, the attendant refilling the fill cups as the level of the water therein gets low.

While a cell is in operation, fluctuations of the gas pressure conditions in a cell are compensated for by the displacement of the electrolyte in the cell through the pipes *h'*, *h²* and *h³*, there being, under such conditions, a movement of the water, or surge thereof, between the cell and the cup. Under such conditions the electrolyte forced from the cell may contain bubbles containing gas which, notwithstanding the presence of the separator, and particularly if no such separator be used, will pass into the cup. Again, if the level of the electrolyte in the cell becomes too low as a result of the cup not being properly filled with water, the gas pressure within the cell will force a small volume of electrolyte and a larger number of gas bubbles through the fill pipes into the cup, this condition being known as a blow-out. Whenever gas bubbles pass from the cell to the fill cup, and particularly when there is a blow-out, these bubbles are inclined to leave the cup and to fall upon the exterior of the cell; but with an attachment made in accordance with my invention, the electrolyte and gases thus forcibly discharged into the cup will be first directed against the baffles *i'*, *i²* and *i³*, the down-turned edges of which will be immersed in water since they extend below the ends of said fill pipe. Hence these baffles will confine the liquid about the tops of said pipes until the gas bubbles have had an opportunity to separate from the liquid, pass through the openings *j* and pass into engagement with the under side of the shield *k* upon which they will ac-

5 cumulate in large numbers, the small bubbles either bursting or merging into larger bubbles, which ultimately burst, so that the gas within the bubbles is released and passes readily through the perforations in said shield the liquid envelop of the bubbles falling toward the bottom of the cap.

10 This condition results from the fact that gas bubbles will not pass through small openings, or in attempting to pass therethrough will adhere to the walls about the openings until presence of other bubbles will cause them all to merge together and break.

15 I have found in actual practice, that an attachment made in accordance with my invention, gives perfect satisfaction in preventing the splashing of electrolyte upon the cell, while at the same time affording 20 a free venting of the cell in the event of excessive pressures therein, the open top of the cup or other means forming the chamber for the feed water, permitting such gases to escape freely to atmosphere.

25 It is not my intention to limit the invention to the precise details of construction shown in the accompanying drawings, it being apparent that such may be varied without departing from the spirit and scope 30 of the invention.

Having described the invention, what I claim as new and desire to have protected by Letters Patent, is:—

1. A water feed attachment for electrolytic cells embodying therein means forming a chamber for feed water, and passages leading from said chamber and discharging within said cell, and a perforated shield within said chamber and above the ends of 40 said passages, whereby gas bubbles emerging from said passages will accumulate upon the under side of said shield, and gas, freed by the bursting of bubbles, will pass through said shield, and the liquid envelop of said bubbles will be returned to said chamber.

45 2. A water feed attachment for electrolytic cells embodying therein means forming a chamber for feed water, and passages leading from said chamber and discharging within said cell, baffles arranged above and adjacent the ends of said passages within said chamber, and a perforated shield within said chamber and above said baffles, whereby gas bubbles entering said chamber 55 will be accumulated upon the under side of said shield, and gas, freed by the bursting of bubbles, will pass through said shield, and the liquid envelop of said bubbles will be returned to said chamber.

60 3. A water feed attachment for electrolytic cells embodying therein means forming a chamber for feed water, and passages leading from said chamber and discharging within said cell, baffles arranged above and

adjacent the ends of said passages within 65 said chamber, said baffles having openings therethrough through which gas bubbles emerging from said passages will escape, and a perforated shield within said chamber and above said baffles, whereby gas bubbles entering said chamber will be accumulated upon the under side of said shield, and gas, freed by the bursting of bubbles, will pass through said shield, and the liquid envelop of said bubbles will be returned to 75 said chamber.

4. A water feed attachment for electrolytic cells embodying therein a fill cup, a plurality of pipes each having one end thereof projecting within said fill cup and the other 80 end thereof communicating with a compartment in the cell, and a perforated shield within said cup and above the ends of said pipes, whereby gas bubbles emerging from said pipes will accumulate upon the under 85 side of said shield, and gas, freed by the bursting of bubbles, will pass through said shield, and the liquid envelop of said bubbles will return to said chamber.

5. A water feed attachment for electrolytic cells embodying therein a fill cup, a plurality of pipes each having one end thereof projecting within said fill cup and the other end thereof communicating with a compartment in the cell, a baffle spaced away 90 from and inclosing the ends of said pipes within said cup, and a perforated shield about and above said baffles, whereby gas bubbles emerging from said pipes will be accumulated upon the under side of said 95 shield, and gas, freed by the bursting of bubbles, will pass through said shield, and the liquid envelop of said bubbles will return to said chamber.

6. A water feed attachment for electrolytic cells embodying therein a fill cup, a plurality of pipes each having one end thereof projecting within said fill cup and the other end thereof communicating with a compartment in the cell, a baffle spaced away 105 from and inclosing the ends of said pipes within said cup, said baffles having openings therethrough through which gas bubbles emerging from said pipes may pass, and a perforated shield about and above said baffles, whereby gas bubbles emerging from said pipes will be accumulated upon the under side of said shield, and gas, freed by the bursting of bubbles, will pass through said shield, and the liquid envelop of said bubbles will return to said chamber.

In witness whereof I have hereunto affixed my signature, this 19th day of April, 1919, in the presence of two subscribing witnesses.

ISAAC H. LEVIN.
